SOCK

Otis W. Holder, Mount Airy, and Walter M. Brown, Jr.,
Burlington, N. C., assignors to Browns Hosiery Mills,
Inc., Burlington, N. C., a corporation of North Carolina

Application March 17, 1958, Serial No. 50,052

Term of patent 14 years

(Cl. D47-7)

The dominant feature of our design resides in the particular knitted leg portion as shown.

We claim:

The ornamental design for a sock, substantially as shown and described.
